Specification for Design.

Patented July 15, 1913.

Application filed April 23, 1913. Serial No. 763,168. Term of patent 14 years.

To all whom it may concern:

Be it known that I, WINTHROP K. HOWE, a citizen of the United States, and a resident of the city of Rochester, in the county of Monroe and State of New York, have invented a new, original, and ornamental Design for a Light-Signal Casing, of which the following is a specification, reference being had to the accompanying drawing, forming part thereof.

Figure 1, is an elevational view of a light

signal casing, showing my new design, and Fig. 2, is a view of the light signal casing, shown by Fig. 1, looked at from the right hand side.

I claim:

The ornamental design for a light signal casing, as shown.
